APPARATUS FOR FILLING BAGS

Boyd W. Rose, Riverside, Calif., assignor to Food Machinery and Chemical Corporation, San Jose, Calif., a corporation of Delaware

Application November 1, 1955, Serial No. 544,179

17 Claims. (Cl. 141—83)

This invention appertains to an apparatus for filling bags with fluids or fluidized solids and more particularly relates to an improved mechanism for supporting and sealing a bag while it is being filled and for releasing the bag after it is filled.

The bag filling apparatus of this invention is an improvement in apparatus of the type in which powdered or granular material is aerated and fluidized to facilitate the delivery thereof into porous bags. In order to fill bags of this type a filling spout, which communicates with the supply tank, is inserted in the inlet passage of the bag and is clamped therein permitting fluidized material to flow through the spout and into the bag. During the filling operation the bottom of the bag rests upon a support structure which carries most of the weight of the bag and material contained therein. After the bag has been filled, the bag is released and allowed to fall free of the filling apparatus. Bag filling apparatus of this type is more fully disclosed in the United States Patent to Paul C. Aust, No. 2,795,389, dated June 11, 1957.

Certain filling and discharging difficulties have been encountered in the use of apparatus of this type. It has been found that quite frequently a bag is successfully filled by the apparatus, but after being released so that it may fall free from the machine, the bag hangs up on the filling spout. The operator must thereafter manually, and usually with considerable difficulty, remove the bag from the spout. Another difficulty encountered with existing apparatus of this type results from the fact that pressure builds up within the bag and forces some of the powdered material to flow between the wall of the bag inlet passage and the filling spout of the mechanism to the outer atmosphere. This results in very disagreeable working conditions and a loss of material.

It is, therefore, an object of this invention to provide a bag filling apparatus which will automatically and dependably release bags, when filled, to thereafter allow them to fall free of the apparatus.

Another object is to provide an improved bag sealing device for a bag filling and discharging apparatus.

Another object is to provide a bag filling apparatus adapted to efficiently support and seal a bag while it is being filled.

Another object is to provide an improved control system for a bag filling and discharging apparatus, said system being adapted to cooperatively control the functions of holding and sealing a bag while being filled and to thereafter cooperatively and automatically control the functions of stopping the flow of material into the bag and releasing the bag so that it may fall free of the bag filling apparatus.

These and other objects of the present invention will be apparent from the following description of the accompanying drawings which illustrate a preferred embodiment thereof and wherein:

Fig. 1 is a fragmentary perspective of a bag filling apparatus embodying the invention.

2

Fig. 2 is a front elevation of a lower portion of the bag filling apparatus of Fig. 1 with certain parts broken away.

Fig. 3 is a side elevation of the bag filling apparatus of Fig. 1, with parts broken away and other parts shown in section.

Fig. 4 is a vertical section taken along the lines 4—4 of Fig. 1.

Fig. 5 is a diagram of the pneumatic control system used with the bag filling apparatus of Fig. 1.

In the bag filling and discharging apparatus of this invention, a bag B (Fig. 5) is placed on a bag support unit 11 which is, in turn, mounted on a scale 12. The bag B is of the type wherein the material enters the bag through a generally tubular portion V that is known as a bag valve. In order to fill the bag B, a filling spout 13, which is in communication with a supply tank 14, is inserted within the valve V of the bag B and is clamped in this position against a stationary clamping structure 15. A fluidized material contained in the supply tank 14 is then directed into the bag B through the filling spout 13. In order to prevent a portion of the fluidized material flowing into the bag from escaping between the valve V and the filling spout 13, a pneumatic bag seal 17 is provided which, when inflated, seals this opening. As the bag B is being filled, the bag and its contents are continuously weighed by the scale 12. When a desired weight of material is reached, the scale automatically activates a pneumatic control system 18 whereby to close a valve mechanism 19 which stops the flow of material into the bag B. Immediately thereafter, the bag seal is deflated and the filling spout is swung away from the clamping structure. Due to the fact that the weight of the bag is disposed on the support structure 11 in an off-center position and to the fact that the upper end of the bag is released from the spout 13, the filled bag swings outwardly and falls free of the apparatus.

More specifically, the apparatus of the present invention comprises the supply tank 14 (Figs. 1 and 3) mounted on the upper portion of a frame structure 21. The tank 14 is arranged to receive a supply of powdered or granular material into which air, or any other suitable fluidizing agent, is introduced through a conduit 22 (Fig. 5) which communicates with the bottom of the tank 14. The air aerates or fluidizes the material contained within the tank 14 to thereby facilitate the ability of the material to flow, and to prevent the formation and dispersal of an excessive amount of dust during the bag filling operation.

The scale 12 (Figs. 1 and 3) comprises two substantially parallel beams 23 and 24 which are integrally connected by a rear bight section 26 (Fig. 3) extending between their ends, and by a transverse member 27 disposed between the beams adjacent their midpoint. Each beam 23 and 24 of the scale 12 is mounted to pivot on a knife edge 28 which projects upwardly from a cross member 29 of the frame structure 21 to contact the associated scale beam substantially at its midpoint. A heavy counterweight 31 is pivotally secured to each of the beams 23 and 24 adjacent the rear end thereof to counterbalance the major portion of weight applied on the scale by the weight of a filled bag. A horizontal bar 32 is secured to and extends between the midpoint of the transverse member 27 and the bight section 26, and has a light counterweight 33 slidably mounted thereon. The counterweight 33 may be selectively positioned along the bar 32 to adapt the scale for use with bags of different capacities. The rearward end of the bight section 26 is provided with a limiting device 34 which swings between upper and lower limits provided by a U-shaped bracket 36 mounted on the frame structure 21. The limiting device 34 prevents excessive vertical movement

of the scale 12. The forward end of each of the beams 23 and 24 (Fig. 1) of the scale 12 is provided with a knife edge 37 which is pivotally engaged in a suitable mating portion near the outer end of one of the arms of a horizontally extending yoke 38 which is, in turn, secured to a vertical support column 39 of the bag support unit 11. Thus the bag support unit 11 is pivotally supported by the scale 12 through the rigid yoke 38.

As will be pointed out presently, the filling spout 13 and a bag cradle assembly 41 (Fig. 1) are pivotally mounted on the vertical column 39 of the bag support unit 11 and the bag clamping structure 16 is rigidly secured on the column. Accordingly, as the bag B is being filled, the entire unit 11 including the filling spout 13, the cradle assembly 41, the bag clamping structure 16, and the column 39 move downwardly to activate the scale 12.

The bag cradle 41 (Figs. 1 and 2) comprises a two-piece vertically extending channel 42 which is arranged to be adjustably lengthened in a vertical direction and is provided at its upper end with a concavely formed bag back rest 43. A horizontally disposed, forwardly directed angle member 44 is secured, as by welding, to each side face of the channel 42 near its lower end. Mounted for horizontal adjustment between the two angle members 44, by means of bolts 46 extending through slots 47 provided in the angle members, are two similar ear-shaped seats 48 and 49 which have convex support surfaces upon which a bag rests during the filling operation.

The cradle assembly 41 is pivotally mounted on a bracket 51 (Fig. 1) which is secured to and projects outwardly from a lower portion of the vertical column 39. The bracket 51 comprises two parallel, horizontal channel members 52 (Fig. 2), which are secured to a face plate 53 and project forwardly beneath the angle members 44. The face plate 53 lies against the forward face of the column 39 and has tabs 54 (Fig. 1) bent at 90° to contact the side surfaces of the column 39 to prevent shifting of the face plate 53 relative to the column 39. A strap 56 is arranged to lie against the rear face and both sides of the column 39 and has a stud 57 secured on each side thereof to project forwardly through suitable apertures provided in the face plate 53. Nuts 58 are threaded on the ends of the studs 57 to firmly secure the bracket 51 to the column 39. Two axially aligned pivot pins 59 (Fig. 2) are provided and are so arranged that one pivot pin 59 extends through one of the channel members 52, of the angle members 44, one of the ear-shaped elements 48 or 49, and one of the two spaced horizontal support members 44, while the other pin 59 extends through the other of the above mentioned parts to mount the bag cradle assembly 41 pivotally in relation to the vertical column 39. It should be noted that the pivot pins 59 (Fig. 5) are horizontally spaced from the vertical column 39 a distance substantially less than the distance between the column 39 and the center of gravity, indicated generally at 61 in Fig. 5, of a filled bag B supported on the cradle assembly 41. Thus, when the upper end of the bag B is released, the weight of the bag will tilt the cradle assembly 41 in a counterclockwise direction (Fig. 3) to thereafter permit the bag to fall free from the cradle 41.

To prevent excessive pivoting of the bag support cradle 41, an abutment arm 62 (Fig. 3) is secured to the lower end of the channel 42 and projects downwardly and forwardly therefrom. When the cradle assembly 41 is swung in a counterclockwise direction (Fig. 3) the abutment arm 62 will swing counterclockwise (Fig. 3) and will contact the lower horizontal edge of the face plate 53, thus preventing further pivoting of the cradle 41. A tension spring 63 (Fig. 2) is positioned between each angle member 44 and each channel member 52 and has an upper end secured to one of the angle members 44 and a lower end secured to the face plate 53 whereby

to return the cradle 41 to the position shown in Fig. 3 after the filled bag has fallen from the cradle.

It will be apparent that during the filling operation the lower end of the bag support unit 11 (Fig. 3) will tend to swing inwardly toward the frame structure 21. Accordingly, a buffer link 64 is pivotally interposed between the lower portion of the vertical column 39 and a bracket 66, which is rigidly attached to the frame 21, to prevent excessive pivoting of the column 39 during the bag filling and discharging operation while permitting free downward movement of the column.

The bag clamping structure 16 is secured on the upper forward face of the column 39, which is forwardly bent as clearly shown in Fig. 3. The structure 16 comprises an upwardly-opening channel bracket 67 (Fig. 1) which projects outwardly from the face of the column 39, on which it is mounted by bolts 68, one only being shown. A pneumatic bag clamping cylinder 69 is mounted on the upper surface of the bracket 67 and has its plunger 71 (Fig. 4) extending rearwardly through a suitable opening 72 provided in the column 39. A stationary clamp element 73 is mounted on the lower end of a downwardly projecting stud 74, which extends through a slot 76 provided in the bottom face of the channel bracket 67 and is locked on the channel by nuts 77. With this arrangement, the stationary clamp element 73 may be adjusted both vertically and horizontally to allow the stationary clamping element 73 to be fixed in the most desirable position for cooperation with the filling spout 13 which acts as the movable clamping element.

The filling spout 13 (Figs. 1 and 4) comprises a rigid filling tube 78 which is secured to and extends through a rigid collar 79 positioned adjacent the inlet end of the spout. The collar 79 is, in turn, rigidly secured to a bracket 81 by any suitable means, such as welding. The terminal end 82 of the filling spout 13 has a downwardly curved upper surface which permits the bag to be easily released therefrom after the bag has been filled. The lower portion of the terminal end 82 of the filling tube 78 has an opening 83, as clearly shown in Fig. 4, to allow fluids or fluidized solids to be discharged from the tube 78 into the bag B. The bracket 81 (Fig. 3), on which the filling spout 13 is mounted, is pivotally mounted on the column 39 by means of bolts 84 (Figs. 1 and 3), only one being shown, which extend through suitably apertured bosses 86, one of which is rigidly secured on each side of the bracket 81. The pivoted position of the bracket 81 is controlled by the plunger 71 (Fig. 4) of the bag clamping cylinder 69. When the plunger 71 is actuated, it contacts a bar 87, which extends transversely through slots 88 in the side walls of the column 39 and which is secured within a pair of spaced bosses 89 (Fig. 1) welded on the upper side surfaces of the bracket 81 in alignment with the slots 88.

When air under pressure is directed into the bag clamping cylinder 69, the plunger 71 (Fig. 4) is pushed out of its cylinder and contacts the bar 87 to pivot the bracket 81 on the bolts 84 whereby the filling spout 13 is swung upwardly into the bag clamping position shown in Figs. 3 and 5. Thus, a bag placed over the filling spout 13 will be firmly locked between the spout and the clamping element 73. When air is released from the cylinder 69, the filling spout 13 is allowed to pivot away from the element 73 by gravity to thereby assume the downwardly inclined bag-releasing position shown in Fig. 4.

The bag seal 17 (Fig. 4) which is made of a flexible, resilient material, such as rubber, is generally tubular in shape and is fitted over the filling tube 78. Near its rearmost end, the seal 17 is securely clamped on the collar 79 by a circular clamp 91. The forward end of the bag seal fits over the filling tube 78 and terminates immediately rearward of the discharge opening 83. The forward portion 92 of the bag seal 17 is slightly thicker in longitudinal cross section than the main body 93 of the seal 17 and is provided with a beveled outer edge 94 in

order that the inlet valve V of the bag B may be easily slid over the bag seal. An annular inner lip 96 of the bag seal 17 extends rearwardly from the forward portion 92 thereof and has an inner surface 97 which contacts the outer surface of the rigid filling tube 78 and an outer surface 98 of slightly larger diameter. A ring-like space 99 is provided between the internal diameter of a portion of the main body 93 and the outside diameter of the annular lip 96. A suitable air supply conduit 101 is secured to and extends within the bag seal 17 to direct air under pressure into the bag seal 17 to cause the annular lip 96 to be forced into an airtight seal around the filling tube 78 and to cause the body 93 of the bag seal 17 to increase in diameter and contact the surfaces of the bag valve V placed therearound to thereby seal the inside of the bag from the atmosphere. Upon release of air pressure, the bag seal 17 collapses and returns to the position shown in Fig. 3.

A flexible tube 102 (Figs. 3 and 4) is connected between the filling spout 13 and the supply tank 14, to allow fluids or fluidized solids to flow from the supply tank 14 to the filling spout 13. The tube 102 is connected to the rearward portion of the filling tube 78 by a clamp 103. The rear end of the tube 102 is connected to the tank 14 by any suitable means, such as by mating flanges 104 and 106 (Fig. 1).

The valve mechanism 19 (Fig. 1) is of the type described in the Letters Patent of Neil S. Stafford, et al., Patent No. 2,770,439, issued November 13, 1956. Since the valve mechanism is not a part of the present invention it will not now be described in detail. In general, the valve mechanism 19 comprises an air motor 111 mounted on an angle bracket 112 which is, in turn, mounted to the forward portion of the frame 21. An upper pinch bar 113 (Fig. 5) and a lower pinch bar 114 are positioned, respectively, above and below the flexible tube 102 leading to the spout 13 and are connected by a suitable linkage 116 (Figs. 1 and 3) which is supported by the angle bracket 112 and is connected to the piston rod 117 (Fig. 5) of the air motor 111. When air is introduced below the piston 118 (Fig. 5) of the air motor 111, the upper pinch bar 113 and lower pinch bar 114 are moved away from each other to the position shown in Figures 3 and 5, allowing the flexible tube 102 to open and the fluids or fluidized solids contained in the tank 14 to flow through the tube 102 into the bag B. When air is introduced above the piston 118, the upper bar 113 and lower bar 114 are forced together to pinch the tube 102, as best shown in Fig. 4, and thus stop the flow of fluids or fluidized solids from the tank 14 into the filling spout 13.

The pneumatic control system 18, which automatically and cooperatively controls the bag filling and discharging operation is shown diagrammatically in Fig. 5. Although other gases may be used as a pneumatic operating medium, air is the preferred gas and, therefore, in the description of the control system 18 to follow, air will be referred to as the operating medium.

Air is introduced into the control system 18 from a suitable high pressure source (not shown) through a conduit 130 and, after passing through a filter 131, the air is divided into three separate portions. One portion of the air flows through a conduit 133 to a pressure regulator 134 and then through the conduit 22 and into the material supply tank 14 to thereby fluidize the material contained therein. The regulator 134 is set at a predetermined pressure found most desirable to fluidize the particular material to be filled into bags.

Another portion of the air flows from the filter 131 through conduits 135 and 136 and to a low pressure regulator 137 which is set at approximately 5 p. s. i. The low pressure air flows from the regulator 137 through a conduit 138 to a three-way valve 139 which comprises an outer housing 141 within which a spool 142 is positioned for vertical movement. The spool 142 may be

upwardly urged by a spring 143 or downwardly urged by a high pressure source of air entering the housing 141 at the top thereof through a conduit 144, as will be more completely described later. An inlet port 146, an outlet port 147, and a vent 148 are so located in the housing 141 of the three-way valve 139 that when the spool 142 is in the upper position of Fig. 5, the inlet port 146 and outlet port 147 are in communication and, when the spool 142 is in the lower position, the vent 148 and the outlet port 147 are in communication while the inlet port 146 is closed. The conduit 101, which delivers air under pressure to the bag seal 17, is connected to the outlet port 147. Thus, when the three-way valve 139 is positioned as shown in Fig. 5, the low pressure air flows from the low pressure regulator 137, through the conduit 138, through the inlet port 146 and out the outlet port 147 of the three-way valve 139, through the conduit 101, and into the bag seal 17 to thereby inflate the seal 17 causing it to expand against the valve V of the bag B. When high pressure air is introduced to the top of the three-way valve 139, thereby forcing the spool 142 downwardly, as viewed in Fig. 5, air is allowed to bleed from the bag seal 17 through the conduit 101, into the outlet port 147 and out the vent 148 of the three-way valve 139 to thereby allow the bag seal 17 to deflate.

Another portion of air from the filter 131 flows to a high pressure regulator 151 through the conduits 135 and 152 and thereafter flows through a conduit 154 to a lubricator 155. A conduit 156 introduces the high pressure air to a master valve 157 which is mounted on top of the air motor 111 as best shown in Fig. 1.

The master valve 157 (Fig. 5) comprises a housing 158 having a cylindrical chamber 159 and a distribution chamber 161. A spool 162, having an annular groove 163 around its midpoint, is slidably mounted within the cylindrical chamber 159 of the housing 158. A small air passageway 164 is provided in the surface of the spool 162 extending longitudinally thereon to thereby allow air to flow to each end of the cylindrical chamber 159 of the housing 158. High pressure air from the conduit 156 enters the master valve 157 through an inlet port 166 and then flows to each end of the cylindrical chamber 159 as previously mentioned. From the chamber 159 air flows through a slot 167 provided in an inner wall 168 of the housing 158 and thereafter into the distribution chamber 161. A slide valve 169 is slidably mounted within the distribution chamber 161 and is connected to the spool 162 by means of an arm 171, which extends through the slot 167 and is received within the annular groove 163 of the spool 162 for movement therewith. In order to be assured of a supply of air at each end of the cylindrical chamber 159, the spool 162 is prevented from contacting the ends of the chamber 159 due to the fact that the arm 171 contacts the end walls of the slot 167 before the spool reaches the end of the chamber 159. The slide valve 169 is provided with two internal chambers 172 and 173 which are sealed from the high pressure air within the distribution chamber 161. In order to provide flow passages between adjacent ports, the chambers 172 and 173 are arranged to overlap different ports provided in the housing 158. When the master valve 157 is positioned as shown in Fig. 5, a port 176 is in direct communication by means of the chamber 173 with a vent 177; a second vent 178 is in communication with the chamber 172; and a port 179 is in communication with the distribution chamber 161 and the high pressure air contained therein. When the spool 162 and the attached slide valve 169 are moved to the left (Fig. 5), the port 176 is opened to the high pressure air contained within the distribution chamber 161, and the port 179 is in communication with the vent 178 through the chamber 172.

The master valve 157 is of the type in which a temporary unbalance of the air pressure on the ends of the spool 162 will cause the spool and attached slide valve

169 to shift position in the housing. This unbalanced condition is achieved by normally closed switches which are in the form of spring loaded air bleeder valves disposed in air conduits which communicate with each end of the cylindrical chamber 159. When one of the switches is held in an open position for a short time, a small amount of air will bleed from one side of the cylindrical chamber 159 causing the above-mentioned unbalanced air pressure and thereby causing the spool 162 to be shifted to the low pressure end.

The above-mentioned switches comprise a manually operated start switch 181, a manually operated stop switch 182 and a scale actuated switch 183. The start switch 181 is conveniently positioned at the front of the machine on the right side of the master valve 157 (Fig. 1) with which it is in communication through a conduit 184. Similarly the stop switch 182 is positioned at the front of the machine on the left side of the master valve 157 (Fig. 1) and is in communication with the left end of the cylindrical chamber 159 of the master valve 157 through a conduit 185. The scale actuated switch 183 (Fig. 3) is mounted on the upper forward portion of the frame structure 21 adjacent the upper end of a lever arm 187 which is secured to and projects upwardly from the cross member 27 of the scale 12. An adjustment bolt 188 is threaded adjacent the upper end of the lever arm 187 and is positioned to contact and actuate the scale switch 183 when the scale 12 is pivoted counterclockwise (Fig. 3) by the weight of a bag which has received a desired quantity of material. The scale actuated switch 183 (Fig. 5) is connected in parallel with the stop switch 182 by the conduit 189.

Thus, when the start switch 181 (Fig. 5) is momentarily actuated, the spool 162 and attached slide valve 169 are forced to slide to the right into the position shown in Fig. 5 allowing air to flow through the port 176, through the chamber 173 and out the vent 177, and also allowing high pressure air contained in the distribution chamber 161 to flow out the port 179. When either the stop switch 182 or the scale actuated switch 183 is momentarily actuated, the spool 162 and the attached slide valve 169 slide to the left (Fig. 5) thereby opening the port 176 to high pressure air contained within the distribution chamber 161 and allowing air to flow from the port 179, through the chamber 172 and out the vent 178 to the outer atmosphere.

The port 179 of the master valve 157 is connected by a conduit 191 to the air motor 111 at a point located below the piston 113. Another conduit 192 connects the port 176 and the air motor 111 at a point above the piston 113. Thus, with the spool 162 of the master valve 157 positioned at the right hand end of the chamber 159 as shown in Fig. 5, high pressure air flows through the conduit 191, raises the piston 113 and opens the valve mechanism 19. At the same time, the air in the upper portion of the air motor cylinder is vented through the conduit 192, the chamber 173, and the vent 177. When the spool of the master valve 157 is positioned at the left hand end of the chamber 159, high pressure air flows through the conduit 192 to the top of the air motor 111 to force the piston 113 downwardly to close the valve mechanism 19. In this case, the lower portion of the air motor cylinder is vented through the conduit 191, the chamber 172, and the vent 178.

A conduit 193 is connected to the conduit 191 to allow air to flow to a needle valve 194 and to a by-pass check valve 195 which are connected in parallel. The by-pass check valve 195 allows air to rapidly flow to the left as viewed in Fig. 5 but prevents air from flowing in the opposite direction. A conduit 196 communicates the needle valve 194 and by-pass check valve 195 with the bag clamping cylinder 69. Thus, when the master valve 157 is positioned as shown in Fig. 5, air rapidly flows from the conduit 193, through the needle valve 194 and by-pass check valve 195, through the conduit 196, and

into the bag clamping cylinder 69 to thereby rapidly pivot the filling spout 13 into a bag clamping position. Upon shifting the spool 162 of the master valve 157 to the left (Fig. 5), air is allowed to slowly escape from the bag clamping cylinder 69, through the conduit 196, and the needle valve 194 and into the valve chamber 172 where it is vented to the atmosphere through the port 178. Thus, with the above arrangement, the filling spout 13 is rapidly pivoted to the bag clamping position but is slowly pivoted away from the bag clamping position into the bag releasing position.

As previously mentioned, the spool 142 of the three-way valve 139 is urged to its upper position in the housing 141 by a spring 143 and is moved to its lower position by high pressure air entering through conduit 144. In order to control the position of the spool 142 within the three-way valve 139, the aforementioned conduit 192, which is connected to the port 176 of the master valve 157, is connected by a branch conduit 197 to a needle valve 198 and a by-pass check valve 199. Air may flow through the by-pass check valve 199 to the left as shown in Fig. 5 but is prevented from flowing in the opposite direction. The needle valve 198 and by-pass check valve 199 are connected to the previously described three-way valve 139 by the conduit 144. When the spool 162 of the master valve 157 is positioned at the right as shown in Fig. 5, air in the conduit 144 is vented through the chamber 173 and the vent 177. This allows the spool 142 of the three-way valve 139 to rapidly move upwardly to the position shown in Fig. 5 to open the conduit 191 leading to the bag seal 17 to inflate the seal with low pressure air. Upon actuating the master valve 157 so that the spool 162 is positioned to the left (Fig. 5), air will flow from the master valve 157 through the port 176, slowly through the needle valve 198, through the conduit 144 and into the three-way valve 139 to thereby slowly move the spool 142 downwardly to shut off the supply of low pressure air to the bag seal 17 and to allow the air contained in the seal to escape to the atmosphere through the vent 143 as previously described.

At the beginning of a bag filling cycle, the apparatus is positioned as shown in Fig. 1. Accordingly, the cradle assembly 41 is positioned with the ear-shaped seats 48 and 49 substantially horizontal so that the bottom of a bag may be placed thereupon; the filling spout 13 is pivoted downwardly away from the stationary clamping element 73; the bag seal 17 is deflated so that the valve of a bag may be easily placed thereover; and the valve mechanism 19 is in its closed position thereby preventing the fluids or fluidized solids contained in the tank 14 from passing into the filling spout 13. The start switch 181 is then momentarily actuated causing the spool 162 of the master valve 157 to assume the position shown in Fig. 5.

High pressure air then flows to the bag clamp cylinder 69 through conduit 196 to thereby pivot the filling spout upwardly into the bag clamping position as shown in Figs. 3 and 5. Simultaneously, air flows to the lower side of the piston of the air motor 111 through conduit 191 to open the valve mechanism 19 and allow fluidized material to flow into the bag B. Also, high pressure air is allowed to bleed from the space above the spool 142 of the three-way valve 139, permitting the spool 142 to move upwardly and open the low pressure air line to the bag seal 17 to inflate the bag seal. When the bag B is filled to the desired weight, the scale 12 is pivoted counterclockwise (Fig. 5) thereby actuating the scale switch 183 and causing the spool 162 of the master valve 157 to be shifted to the left.

A portion of the high pressure air is then directed through conduit 192 to the top of the cylinder of the air motor 111 to thereby rapidly close the valve mechanism 19, stopping the flow of fluidized material into the bag B. A second portion of high pressure air slowly flows into the three-way valve 139 through conduit 144 to force

spool 142 downwardly to establish communication between the conduit 101 and the vent 148 whereby to bleed air from the bag seal 17. Also, the bag clamping cylinder 69 is vented through the conduit 196, needle valve 194, conduit 193, chamber 172 and vent 178 permitting the filling spout to swing downwardly to an inclined position wherein the bag may slide off the spout. The delayed deflation on the bag seal 17 and release of the bag clamping cylinder 69 allows time for material within the filling spout 13 to drain into the bag B.

After the bag has been filled and released from the spout 13, the weight of the bag acting through the offset center of gravity pivots the entire bag support cradle 41, including the back rest 43, forwardly so that the bag may then fall free from the cradle onto a conveyor or any other suitable means provided to remove the bag from the area.

In the above-described bag filling and discharging apparatus, the novel pivotal mounting of the filling spout provides means for dependably releasing a bag from the spout thereby eliminating the possibility of the bag hanging up on the spout. Furthermore, the pivotal movement of the spout provides effective means of clamping a bag thereon when being filled. The novel inflatable bag seal, heretofore unused on apparatus of this type, prevents the loss of material during the bag filling operation and provides greatly improved working conditions for the operator.

While the apparatus of this invention has been described in connection with the filling of bags of the type having generally tubular inlet valves in the upper portion of the bag, it will be understood that the apparatus may be used to fill, not only bags of this type, but any bag in which the inlet opening is in the upper portion of the bag. Accordingly, in the following claims the term bag valve is used in a generic sense to indicate that portion of a bag which is immediately adjacent to and surrounds the bag inlet opening.

While the preferred embodiment of the present invention has been shown and described, it will be understood that various changes and modifications may be made without departing from the spirit of the invention or scope of the appended claims.

Having thus described the present invention and the manner in which the same is to be used, what is claimed as new and desired to protect by Letters Patent is:

1. In an apparatus for filling a bag of the type which has an inlet valve at the upper end, the combination of a bag support seat mounted for pivotal movement from a substantially horizontal bag supporting position to a downwardly inclined bag discharge position, a filling spout pivotally disposed above said bag support seat and arranged to be received within the inlet valve of a bag disposed on said seat when said seat is in said bag supporting position, a stationary clamp element mounted above and closely adjacent said filling spout, actuating means pivotally mounting said filling spout for movement from a substantially horizontal bag clamping position closely adjacent said clamp element wherein the valve of the bag is clamped between said stationary clamp and said filling spout to a downwardly inclined bag releasing position removed from said clamp element, valve means operatively connected to said filling spout for opening and closing the flow passage through said spout, and control means operatively connected to said actuating means and to said valve means and arranged to consecutively cause a rapid closing of said valve means to stop the flow of material through the spout and a slow downward pivotal movement of said filling spout into the bag releasing position.

2. In an apparatus for filling a bag having an inlet valve at its upper end, the combination of a bag support seat arranged to receive the bottom of a bag to be filled,

a filling spout disposed above the bag support seat and arranged to be received within a tubular inlet valve at the upper end of a bag disposed on said support seat, an inflatable sealing member encircling said filling spout and arranged to be inflated into sealed contact between said spout and the inner surface of the bag valve, means mounting said filling spout for pivotal movement from a substantially horizontal bag filling position to a downwardly inclined bag releasing position, fluid pressure means operable to inflate said bag seal, and control means operatively connected to said seal and to said filling spout mounting means and arranged to retard the deflation of said seal and retard the pivotal movement of said filling spout into the bag releasing position to assure completion of the emptying of the spout prior to the release of the bag from the filling spout.

3. In an apparatus for filling a bag of the type which has a tubular inlet valve at the upper end, the combination of a bag support seat mounted for pivotal movement from a substantially horizontal bag supporting position to a downwardly inclined bag discharge position, a filling spout disposed above said bag support seat and arranged to have the tubular inlet valve of a bag positioned thereover when said seat is in bag supporting position, a tubular inflatable bag seal disposed around said filling spout between said spout and said inlet valve and arranged to be expanded into sealed contact against the inner surface of the inlet valve, a stationary clamp mounted above and closely adjacent said filling spout, means pivotally mounting said filling spout for upward movement from a downwardly inclined bag releasing position to a substantially horizontal bag clamping position wherein the tubular valve of the bag is clamped between said stationary clamp and said filling spout, and control means operatively connected to said bag seal and to said filling spout mounting means for rapidly inflating said seal and rapidly pivoting said filling spout into bag clamping position, and thereafter causing slow pivotal movement of said filling spout into bag releasing position to effect draining of material from the spout prior to the release of the bag from the filling spout, and causing slow deflation of said seal to maintain dust sealing engagement with the bag until filling is completed.

4. In an apparatus for filling a bag of the type which has an inlet valve adjacent its upper end, the combination of a scale, a support member pivotally mounted on the beam of the scale, a bag support seat pivotally mounted adjacent the lower end of said support member and projecting outwardly therefrom to receive the bottom of a bag to be filled, said seat being arranged to be pivoted from a substantially horizontal position to a downwardly inclined bag releasing position, a filling spout pivotally mounted on said support member adjacent the upper end thereof and extending outwardly from said support member above said support seat and arranged to have the inlet valve of the bag disposed thereover, and means operably connected to said spout for swinging said spout from a substantially horizontal bag filling position to a downwardly inclined bag release position, said filling spout and said support member being arranged to pivot independently of each other to the bag releasing position.

5. In an apparatus for filling a bag having a tubular inlet valve, a filling spout receivable within the tubular inlet valve of a bag, an inflatable bag sealing element disposed on said spout between said spout and the inner surface of the tubular inlet valve of the bag, said element comprising a flexible resilient tubular body clamped at one end to the outer surface of said spout, and an annular inturned lip formed on the other end of said body and projecting internally of the body toward said one end of said body and arranged to lie close against the outer surface of said spout, and means for directing

air under pressure into the space between said spout and said tubular body.

6. In an apparatus for filling a bag of the type which has a tubular inlet valve adjacent its upper end, the combination of a bag support seat adapted to receive in supporting relation the bottom of a bag to be filled, a filling spout disposed over said support seat and arranged to be received within the inlet valve of a bag on said seat, an inflatable bag seal disposed on the filling spout between the spout and the valve and arranged to contact the inner surfaces of the tubular bag valve upon being inflated, a conduit for directing fluid under pressure to said seal to inflate the seal, a first valve arranged to control flow of fluid through said conduit, means pivotally mounting said filling spout for movement from a substantially horizontal position to a downwardly inclined position, power means operably connected to said pivotal mounting means, a conduit for directing pressurized fluid to said power means, a second valve in the conduit to said power means for controlling the energization and deenergization of said power means, and control means operatively connected to said first and second valves and arranged to actuate said valves to one setting to effect a substantially simultaneous upward pivoting movement of said spout to a substantially horizontal bag filling position and an inflation of the bag seal into sealing contact against the bag valve, said control means also being arranged to actuate said valves to a second setting to bleed fluid from said bag seal and to bleed air from said power means to allow the filling spout to pivot to a downwardly inclined bag releasing position.

7. In an apparatus for filling bags with fluids or fluidized solids the combination of a column, a filling spout pivotally mounted on said column and projecting outwardly therefrom and arranged to be received within the inlet valve of a bag, a clamping element secured to said column and disposed directly above said filling spout, an actuating mechanism for pivoting said spout, a pneumatic power cylinder mounted on said clamping structure and operatively associated with said actuating mechanism to pivot said filling spout upwardly toward said clamping structure when subjected to pneumatic pressure whereby to clamp the inlet valve of a bag on said spout between said spout and said clamping element, and control means associated with said power cylinder and arranged to direct air to said cylinder to effect the upward movement of said spout to bag clamping position, and arranged to bleed air from said power cylinder to allow said spout to gravitate away from said clamping element.

8. In an apparatus for filling a bag having an inlet opening adjacent the upper end of the bag, the combination of a bag support seat arranged to receive the bottom of a bag to be filled, a filling spout disposed above the bag support seat and arranged to be received within the inlet opening at the upper end of a bag on said seat, supporting means pivotally mounting said filling spout for pivotal movement from a substantially horizontal bag filling position to a downwardly inclined bag releasing position, a control valve disposed at the inlet end of said spout and arranged to control flow of material into the spout, actuating means arranged to move said valve between a position stopping flow of material into said spout to a position permitting the flow of material into said spout, power cylinders operatively connected to said spout mounting means and to said valve actuating means, conduit means arranged to communicate each power cylinder with a source of fluid under pressure, a master valve disposed in said conduit means and arranged to control flow of fluid through said conduit means, and control means operably connected to said master valve and arranged to move said master valve to one setting wherein the power cylinder connected to said control valve actuating means is energized

to open said control valve and allow material to flow into the filling spout and wherein the power cylinder connected to said spout mounting means is energized to pivot said spout to said substantially horizontal bag filling position.

9. In an apparatus for filling a bag of the type that has an inlet valve at the upper end thereof, the combination of a scale having a pivotal balance beam, a support structure pivotally mounted on the balance beam of said scale, a stationary clamp mounted on said support structure and projecting outwardly therefrom, a filling spout pivotally mounted on the support structure below said stationary clamp, said spout being arranged to be received within the valve of a bag to be filled and to be pivoted from an upper position closely adjacent said stationary clamp to a downwardly inclined bag release position, power means operatively associated with said spout and arranged upon being energized to pivot said spout to said upper bag clamping position and arranged upon being deenergized to permit said spout to pivot to said bag release position, a fluid pressure system for supplying fluid under pressure to said power means, a control member in said system and disposed to be actuated by said balance beam after a predetermined pivotal movement of the beam to deenergize said power means whereby said filling spout is pivoted away from the stationary clamp into the bag releasing position to thereafter allow the bag to fall free of the filling spout.

10. In an apparatus for filling a bag of the type which has a tubular inlet valve adjacent its upper end, the combination of a support structure, a stationary clamping element projecting outwardly from said structure, a filling spout mounted on said support structure for pivotal movement from a substantially horizontal bag filling position closely adjacent to and below said clamping element to a downwardly inclined bag release position, said spout being receivable within the tubular inlet valve of the bag, an actuating linkage connected to said pivotal spout for pivoting the same, power means arranged to actuate said linkage when energized, an inflatable bag seal disposed closely around said spout between said spout and the inner surface of the tubular inlet bag valve on said spout, said seal being arranged upon being inflated to sealingly contact the inner surface of the inlet valve and when deflated to be loosely disposed in the valve, a conduit for supplying air under pressure to said inflatable seal, a valve in said conduit arranged to be moved between open and closed positions to control the flow of air through the conduit, control means operatively associated with said power means and with said valve and arranged to open said valve and energize said power means to substantially simultaneously inflate said bag seal and swing said spout upwardly to bag filling position to clamp the bag between the spout and said clamping element.

11. An apparatus according to claim 10 wherein said control means is operatively associated with said power means and with said valve to deenergize said power means and close said valve to substantially simultaneously pivot said spout to the downwardly inclined bag release position and release pressurized air from said bag seal.

12. In an apparatus for filling a bag of the type which has a tubular inlet valve adjacent the upper end of the bag, the combination of a vertical support member, a bag seat secured to the lower end of said support member and projecting outwardly therefrom to receive the bottom of a bag to be filled, a filling spout pivotally mounted on said vertical support member directly above said bag seat and adapted to be received within the tubular inlet valve of a bag on said seat, an actuating linkage connected to said spout and arranged upon being actuated to pivot said spout between a downwardly inclined position and a substantially horizontal bag filling

position, a first power cylinder operatively connected to said actuating linkage, a flexible conduit communicating with the inlet end of said filling spout for directing material into said spout, a pincher valve mechanism operatively associated with said flexible conduit, a lever system connected to said pincher valve and arranged upon being actuated to move the valve from a closed position in flow restricting pinching engagement with said flexible conduit to an open position wherein the valve is substantially disengaged from said flexible conduit, a generally tubular inflatable bag seal disposed around said filling spout between said spout and the inner surface of the tubular inlet valve of the bag, a conduit communicating said bag seal with a source of pressurized fluid, a flow control valve disposed in said conduit and movable between open and closed positions to control flow of fluid through the conduit, and control means operatively associated with said spout actuating linkage, said pincher valve lever system, and said flow control valve and arranged to actuate said linkage, said lever system and said valve to predetermined positions to effect the substantially simultaneous upward swinging of said spout to the bag filling position, the movement of said pincher valve to open position, and the inflation of said bag seal.

13. A bag filling apparatus comprising a support structure, a supply tank mounted on said support structure on the upper portion thereof, a scale mounted on the support structure disposed below said supply tank and having a balance beam projecting forwardly from said support structure, a vertically extending column pivotally mounted on said balance beam, a pivotal guide linkage connected between said column and said support structure and arranged to limit lateral movement of said column, a bracket mounted for vertical adjustment on the lower portion of said column and projecting forwardly therefrom, a support seat pivotally mounted on said bracket for pivotal movement from a substantially horizontal position to a position inclined downwardly in a direction away from said column, a vertically adjustable member mounted on said seat and disposed adjacent said column and projecting upwardly from said seat, a back rest secured on the upper portion of said vertically adjustable member, a filling spout bracket pivotally mounted at its lower end on said column adjacent the upper end thereof, a bar at the upper end of said filling spout bracket and having its axis parallel to the pivotal axis of said filling spout bracket, a filling spout mounted on said filling spout bracket and projecting forwardly therefrom over said bag support seat, a stationary clamping structure adjustably mounted on the upper portion of said column and disposed immediately adjacent and above said filling spout, a pneumatic power cylinder mounted on said clamping structure and disposed adjacent the bar at the upper end of said bracket, a plunger movable in said cylinder and arranged to be forced outwardly of the cylinder when the cylinder is energized to contact said bracket bar and pivot said spout to a position adjacent said stationary clamping structure, a flexible tube connected between said supply tank and said filling spout whereby to direct material from said supply tank into said filling spout, a pincher valve mounted on said support structure adjacent the upper end thereof and including pinching elements disposed above and below said flexible tube, said valve being arranged when actuated to collapse said tube to block the flow of material therethrough, and pneumatic means associated with said pincher valve and said pneumatic power cylinder for directing pressurized air to said valve and to said power cylinder.

14. In an apparatus for filling a bag of the type having an inlet opening adjacent the upper end, the combination of a bag support seat mounted for pivotal move-

ment from a substantially horizontal bag supporting position to a downwardly inclined bag discharge position and arranged to receive the bottom of a bag to be filled, a bag back rest rigid with and positioned above said seat and arranged to engage the upper portion of a bag supported on said seat and for maintaining the bag in a vertical position, a filling spout disposed above the bag support seat and said bag back rest and arranged to be received within the inlet opening of a bag disposed on said seat, clamp means mounted adjacent to and above said filling spout for clamping the bag against said spout, and means for releasing said bag from said bag clamping means, said bag support seat being arranged to pivot to the bag discharge position simultaneously with the release of said bag from the filling spout whereby said bag back rest is caused to pivotally sweep past said filling spout to aid in the withdrawal of the filling spout from within the bag inlet opening.

20 15. In an apparatus for filling a bag of the type having an inlet opening adjacent the upper end, the combination of a bag support seat mounted for pivotal movement from a substantially horizontal bag supporting position to a downwardly inclined bag discharge position and arranged to receive the bottom surface of a bag to be filled, a bag back rest rigid with and positioned above said seat and arranged to engage the upper portion of a bag supported on said seat, a filling spout disposed above the bag support seat and said bag back rest and arranged to be received within the inlet opening at the upper end of a bag disposed on said seat, a stationary clamp member mounted above the filling spout, and means pivotally mounting said filling spout for movement from a downwardly inclined bag releasing position to a substantially horizontal bag clamping position closely adjacent said clamp member whereby the portion of the bag above said inlet opening is clamped between said stationary clamp and said filling spout, said bag support seat being arranged to pivot to the bag discharge position simultaneously as said filling spout is pivoted to the bag releasing position whereby said bag back rest is caused to sweep past said filling spout to aid in the withdrawal of the filling spout from within the bag inlet opening.

45 16. In an apparatus for filling bags with fluids or fluidized solids the combination of a column, a filling spout pivotally mounted on said column and projecting outwardly therefrom and arranged to be received within the inlet valve of a bag, a clamping element secured to said column and disposed directly above said filling spout, an actuating mechanism for pivoting said spout, power means supported by said column and operatively associated with said actuating mechanism to pivot said filling spout upwardly toward said clamping structure when actuated whereby to clamp the inlet valve of a bag on said spout between said spout and said clamping element, and control means associated with said power means and arranged to actuate said power means to effect the rapid upward movement of said spout to bag clamping position, and thereafter arranged to deactivate said power means to allow said spout to slowly gravitate away from said clamping element.

65 17. In an apparatus for filling a bag having an inlet opening adjacent its upper end, the combination of a bag support seat arranged to receive in supporting relation the bottom of a bag to be filled, means mounting said seat for pivotal movement from a substantially horizontal bag supporting position to a downwardly inclined bag discharge position, a filling spout disposed above the bag support seat and arranged to be received within the inlet opening at the upper end of a bag disposed on said seat, clamping means disposed above and closely adjacent said filling spout, means pivotally mounting said filling spout for movement from a substantially horizon-

15

tal bag filling and clamping position to a downwardly inclined bag releasing position, and control means operatively connected to said spout mounting means and arranged to release said spout for downward pivoting movement prior to the downward pivoting movement of said bag support seat.
